METAL-CLAD PLATE TYPE RHEOSTAT

George L. McFarland, Jr., and Ernest F. Goetz,
Schenectady, N. Y., assignors to General Electric Company, a corporation of New York

Application October 21, 1948, Serial No. 55,702

5 Claims. (Cl. 201—53)

1

This invention relates to improvements in rheostats, and more particularly to metal clad plate type rheostats.

Demand for this type of rheostat has resulted in continual research by manufacturers and others to provide improvements which will increase the life of such rheostats; reduce the manufacturing cost; minimize the mounting space required; and increase the wattage rating for a given size of rheostat.

It is an object of this invention to provide a rheostat in which improvements as outlined above are obtained.

These and additional objects not outlined above will be apparent to those skilled in the art from a consideration of the following specification and the accompanying drawing, wherein Fig. 1 is a plan view of a rheostat embodying our invention, with a section of the cover broken away; Fig. 1a is a cross sectional view taken on line 1a—1a of Fig. 1; Fig. 2 is a cross sectional view of a portion of the rheostat taken on line 2—2 of Fig. 1; Fig. 3 is a cross sectional view of a portion of the rheostat taken on line 3—3 of Fig. 1; Fig. 4 is a cross sectional view taken on line 4—4 of Fig. 1; Fig. 5 is a cross sectional view of a portion of the rheostat taken on line 5—5 of Fig. 4; and Fig. 6 is an enlargement of a portion of the cross sectional view shown in Fig. 4.

Referring to the drawing, Fig. 1 shows the operating side of a rheostat 1 illustrative of one form of this invention. This rheostat includes a circular wiring plate 2 which is made of suitable insulating material and has a projection 3 extending radially beyond the periphery of the plate. Mounted on wiring plate 2 are U-shaped resistance elements 4 having legs 4a and 4b. Legs 4a are approximately radially disposed on the operating face of wiring plate 2 and terminate opposite a ring of apertures 5 in the wiring plate. Legs 4b are similarly disposed on the opposite face of the wiring plate 2. However, with respect to each resistance element 4, leg 4a terminates at aperture 5 next following the aperture 5 at which leg 4b terminates. L-shaped contacts 6, each having one long and one short arm are positioned with the short arms projecting through the apertures 5 and the long arm projection beyond the edge of an aperture 7 centrally located in the wiring plate. Contacts 6 are welded to resistance elements 4 in such a manner as to place the resistance elements 4 in series circuit relation. This is accomplished by welding the legs 4a and 4b of each resistance element to adjacent contacts 6. Legs 4a are welded to the end of the short arm of the contacts 6 adjacent the bend in the L, and the legs 4b are welded to the other end of the short arm

2

of the contacts 6. A brief glance at Fig. 4 will show these elements in further detail.

Terminals 8 and 9 are moulded into the projection 3 of the wiring plate 2, and are electrically connected, respectively, to the first and last of the contacts 6 by conducting strips 10 and 11. A terminal 12 is likewise moulded into the projection 3 of the wiring plate 2 and is located between terminals 8 and 9. The terminal 12 is electrically connected to a collector ring (to be described later) by a conductor strip 13.

To show the manner in which terminal 8 is connected to the first of contacts 6 of the series circuit, Fig. 2, is provided. This cross sectional view taken on line 2—2 of Fig. 1 shows contact strip 10 connected between terminal 8 and the bent portion of the first of contacts 6. Leg 4b of the first of resistance elements 4 is connected to the end of the short arm of the same contact 6.

To show the manner in which the terminal 9 is connected to the last of contacts 6 of the series circuit Fig. 3 is provided. This cross sectional view, taken on line 3—3 of Fig. 1, shows contact strip 11 connected between terminal 9 and the end of the short arm of the last of contacts 6. Leg 4a of the last of the resistance elements 4 is connected to the bent portion of the same contact.

To show the operating means and further structural detail of the rheostat a cross sectional view on line 4—4 of Fig. 1 is shown in Fig. 4. This view shows that the rheostat is provided with a circular bearing hub 14. Bearing hub 14 is made of suitable insulating material, is centrally located on the operating side of the rheostat 1, and serves several functions which I shall now describe.

First, the inner face of the bearing hub 14 is recessed to provide an annular surface 14a which presses against the longer arm of the L-shaped contacts 6 and holds the contacts in position against the inner face 2a of the wiring plate 2. The bearing hub is itself secured by a metallic cover plate 15 which has an aperture 15a of sufficient size to pass over the projecting portion 14b of the bearing hub 14 and allows the cover plate 15 to press against the flanged portion 14c of the bearing hub 14. A similar cover plate 16 rests against flanged surface 2b of the wiring plate 2 on the other side of the rheostat from the operating side and the corners 17 of the two plates 15 and 16 are flattened and welded together as shown in Fig. 1A. In this manner the bearing hub 14 is secured in the rheostat and the contacts 6 are held between adjacent surfaces of the wiring plate 2 and the bearing hub 14.

In bearing hub 14, an aperture 18 is also provided into which a bushing 20 (shown in Figs. 4, 5 and 6) is molded as an insert and receives an operating shaft 19. The portion 19a of the shaft 19 is of reduced cross section, threaded at

its end, and has two flat sides 19b and 19c, (best seen in Fig. 6). Side 19c is slightly tapered so that the portion 19a of the shaft 19 has a diminishing cross section in the direction of its threaded end.

We provide a brush housing 21 having a metal insert plate 22 approximately rectangular in shape moulded thereinto. Insert plate 22 is perpendicular to the axis of the operating shaft 19 when the brush housing 21 is assembled on portion 19a of shaft 19, and has a central aperture 22a to conform approximately to the cross section of 19a in order that the insert plate 22 carrying the brush housing 21 may be forced on the portion 19a of the shaft 19 by a lock washer 23 and nut 24. As so assembled there is no play between the portion 19a of the shaft and the metal insert plate 22 because any clearances which might be present are taken up by the taper of the face 19c of the shaft. When forced on the shaft by the nut 24, the insert plate 22 comes to rest against an abutment 19d formed by the reduction in cross section of the portion 19a of the shaft. An L-shaped operating handle 25 is secured to the other end of the operating shaft 19 and the small arm 25a of handle 25 rides in a groove 14e in the operating face of the bearing hub 14. The inner surface of the longer arm 25b of the L-shaped handle abuts against the end of bearing 20. Thus shaft 19 supports the brush housing 21 which rotates with shaft 19 as the latter is turned by means of the operating handle 25.

Bearing hub 14 is also provided with an annular flange 14d adapted to support a collector ring 26. The collector ring 26 is biased to rest against flange 14d by a collector brush 27 which is brazed to a brush support 28. A contact brush 29 is also brazed to the brush support 28 at a point diametrically opposite to brush 27 and is biased to ride on the contacts 6 as the shaft 19 is rotated. Means for biasing brushes 27 and 29 comprises two springs 30 and 31 which are secured respectively in diametrically opposed recesses 30a and 31a in the inner face of the brush housing 21. Both springs 30 and 31 are secured to the brush support 28 by any suitable means. The operating shaft 19 is thus adequately insulated from the electrical circuits by the bearing hub 14 and the brush housing 21. Also the brushes are easily changed by simply removing the brush housing 21. Furthermore, the springs 30 and 31 cannot be lost during this operation since they are secured to both the brush support 28 and the brush housing 21.

In reviewing the functions of the bearing hub 14, it is seen that hub 14 serves to hold the L-shaped contacts 6 in place against the inner face 2a of the wiring plate 2; further, bearing hub 14 provides an aperture to receive the bearing 20 which in turn secures the operating shaft 19 on which are mounted the operating handle 25 and the brush contact means; and bearing hub 14 also provides a seat to support the collector ring 26. A further function of the bearing hub 14 will be discussed later in relation to adjustable stops to be described in detail.

To aid in securing contacts 6, conductor strip 13, and resistance elements 4, and to provide further insulation and protection for these members, a casting cement is poured into the portion of the rheostat between the plates 15 and 16 as indicated in Fig. 4. When this mixture has hardened it provides insulation and a firm support for these elements and is itself protected from damage by the cover plates 15 and 16.

To enable the operator to set the voltage or speed of his machine adjustable stops in the form of identical circular plates 32 and 33 are provided and are positioned as shown in Figs. 1 and 4. Referring to Fig. 4 it will be seen that both plates are centrally apertured to permit bearing 20 to pass through the apertures as the plates are secured to the operating face of bearing hub 14.

Fig. 1 shows that the diameter of the plates 10 is made approximately equal to the diameter of the internal edge of groove 14e to permit the small arm 25a of the L-shaped handle 25 to ride in groove 14e. Plates 32 and 33 are provided with projections 32a and 33a which overlap the groove 14e and lie in the path of the small arm 25a of the operating handle 25. The position of these projections may be adjusted to provide stops for the handle 25 by means of arcuately shaped slots 32b and 33b through which cap 15 screws 34 are inserted to secure the plates 32 and 33 to the face of bearing hub 14. Once the projections 32a and 33a are set in a particular position by rotating the plates 32 and 33 with respect to the bearing hub 14 the cap screws 34 may then 20 be tightened to secure the plates in the selected positions and thus provide two stops for the rotation of the operating handle 25.

To provide a means for mounting the rheostat the flattened and welded corners 17 of the covers 30 15 and 16 are apertured as at 17a.

The rheostat as illustrated and described herein has an appreciable advantage in wattage rating over conventional rheostats now in use. As an example, in contrast to a conventional 35 rheostat of a size presently manufactured, our rheostat of similar size has a rating of approximately three times that of the conventional rheostat. This increase in wattage is due to the fact that the level of temperature in the entire rheostat may be raised approximately 50° higher than that of conventional rheostats without destroying the utility of the rheostat. This higher temperature is made possible in part by the use of metal covers which hold the structure mounting plates 40 together and in operable form even though the cement or wiring plate is cracked by heat. It is also due in part to a balance of temperature resulting from the use of U-shaped resistance elements having one leg on each side of the wiring 45 plate, so that the heat is not concentrated on one side. It is further facilitated by the use of the metal covers and the casting cement wherein the casting cement conducts the heat to the metal covers which tend to spread the temperature 50 more evenly and also conduct the heat away through the flattened and welded mounting corners.

Use of the flattened and welded mounting corners also provides an advantage in lowering the 60 cost of production and minimizing mounting space, as contrasted with the conventional method of securing mounting legs to the rheostat.

Although an exemplary form of the invention has been shown in the accompanying drawings 65 and described herein in detail, it is to be understood that the disclosures are not intended to be restrictive but that each may embody various modifications in detail structure without departing from the spirit of the invention or the scope 70 of the appended claims.

What we claim as new and desire to secure by Letters Patent of the United States is:

1. A plate type rheostat comprising a mounting plate having a first central aperture, an outer 75 ring of approximately radially disposed resist-

ance elements mounted thereon, an inner ring of radially disposed contacts electrically connected to said resistance elements and forming a series circuit of said elements, said contacts lying against a face of said plate and projecting into said first central aperture, terminal means for said series circuit, a dielectric bearing hub having a second central aperture, said hub overlying said first central aperture and an inner peripheral portion of said mounting plate and lying against said ring of radial contacts thereby to press said contacts against the face of said mounting plate and to hold said contacts in alignment, a contact ring centrally mounted upon said bearing hub and radially inwardly spaced from said ring of contacts, terminal means for said contact ring, a cover plate overlying said mounting plate and a peripheral portion of said hub to hold said mounting plate and said hub together, an operating shaft mounted in the central aperture of said hub, and a pair of angularly spaced electrically connected brushes mounted upon said shaft and engaging said ring and said contacts respectively.

2. A plate type rheostat comprising a circular mounting plate having a first circular central aperture, an outer ring of approximately radially disposed resistance elements mounted thereon, an inner ring of radially disposed contacts electrically connected to said resistance elements and forming a series circuit of said elements, said contacts lying against a face of said plate and projecting into said first central aperture, terminal means for said series circuit, a dielectric bearing hub having a second central aperture, said hub overlying said first central aperture and an inner peripheral portion of said mounting plate and lying against said ring of radial contacts thereby to press said contacts against the face of said mounting plate and to hold said contacts in alignment, a contact ring centrally mounted upon said bearing hub and radially inwardly spaced from said ring of contacts, terminal means for said contact ring, a pair of substantially rectangular metallic cover plates disposed on opposite sides of said mounting plate, one of said cover plates overlying a peripheral portion of said hub to hold said mounting plate and hub together and said cover plates being flattened and connected together at their corners and apertured to form a mounting means for said rheostat, an operating shaft mounted in the central aperture of said hub, and a pair of angularly spaced electrically connected brushes mounted upon said shaft and engaging said ring and said contacts respectively.

3. A plate type rheostat comprising a circular plate having a contact aperture, an outer ring of approximately radially disposed resistance elements mounted thereon, an inner ring of radially disposed contacts electrically connected to said resistance elements and forming a series circuit of said elements, said contacts projecting into said aperture, terminal means for said series circuit, a contact ring centrally disposed in said aperture and having terminal means, a dielectric bearing hub arranged to press said contacts against a face of said plate and to maintain said contacts in position, said bearing hub having a central aperture, a metallic cover arranged to maintain said plate and said bearing hub in fixed position relative to each other,

an operating shaft mounted in the aperture of said hub, a dielectric brush support secured to one end of said operating shaft, and spring biased contact brushes in said brush support, one of said brushes engaging said ring of radially disposed contacts and the other of said brushes engaging said contact ring.

4. A plate type rheostat comprising a circular plate having a central aperture, an outer ring of approximately radially disposed resistance elements mounted thereon, an inner ring of radially disposed contacts electrically connected to said resistance elements and forming a series circuit of said elements, said contacts projecting into the aperture, terminal means for said series circuit, a contact ring centrally disposed in said aperture and having terminal means, a dielectric bearing hub arranged to press said contacts against a face of said plate and to maintain said contacts in position, said bearing hub having a central aperture, a metallic cover arranged to maintain said plate and said bearing hub in fixed position relative to each other, an operating shaft mounted in the aperture of said hub, said cover being flattened at its corners and apertured to form a mounting means for said rheostat, a dielectric brush support secured to one end of said operating shaft, and spring biased brushes in said brush support, one of said brushes engaging said ring of radially disposed contacts, and the other of said brushes engaging said contact ring.

5. A plate type rheostat comprising a circular plate having a central aperture, an outer ring of approximately radially disposed resistance elements mounted thereon, an inner ring of radially disposed contacts electrically connected to said resistance elements and forming a series circuit of said elements, said contacts projecting into said aperture, terminal means for said series circuit, a contact ring centrally disposed in said aperture and having terminal means, a dielectric bearing hub arranged to press said contacts against a face of said plate and to maintain said contacts in position, said bearing hub having a central aperture, a metallic cover adapted to maintain said plate and said bearing hub in fixed position relative to each other, an operating shaft mounted in the aperture of said hub, said cover being flattened at its corners and apertured to form a mounting means for said rheostat, a dielectric brush support secured to one end of said operating shaft, spring biased brushes in said brush support, one of said brushes riding on said ring of radially disposed contacts and the other riding on said contact ring, said metallic cover being filled with casting cement.
